UNITED STATES PATENT OFFICE.

EDGAR H. FREEMAN, OF TRENTON, NEW JERSEY, ASSIGNOR TO E. H. FREEMAN ELECTRIC COMPANY, OF TRENTON, NEW JERSEY, A CORPORATION OF NEW JERSEY.

PULL-CHAIN GUIDE.

1,096,421.

Specification of Letters Patent. Patented May 12, 1914.

Application filed September 1, 1911. Serial No. 647,300.

To all whom it may concern:

Be it known that I, EDGAR H. FREEMAN, a citizen of the United States, residing at Trenton, in the county of Mercer and State 5 of New Jersey, have invented certain new and useful Improvements in Pull-Chain Guides, of which the following is a specification.

This invention relates to chain guides for 10 electrical pull sockets, and has in view an improved construction of guide possessing all of the characteristics and functions of the conventional one-piece pull chain guide or horn, while at the same time providing 15 means whereby the main guiding member or bell may be readily and conveniently handled for reburnishing purposes.

A further object of the invention is to provide an improved pull chain guide which is 20 in the form of an attachment to the shell member of the socket casing, and is held in operative position by the socket cap when placed in position. In this connection the invention also contemplates a guide attachment 25 which is readily and freely detachable from the shell member of the casing, so that the switch mechanism can be readily handled in being inserted and removed from the casing without interference from the chain.

With these and other objects in view, which will be readily apparent to those skilled in the art, the invention consists in the novel construction, combination and arrangement of parts hereinafter more particularly described, illustrated and claimed.

While susceptible of embodiment in various ways by the use of different mechanical equivalents, the invention is exemplified by the preferable form thereof shown in the 40 accompanying drawings, in which—

Figure 1 is an external view of an electrical pull socket casing fitted with a pull chain guide constructed in accordance with the present invention. Fig. 2 is a vertical 45 sectional view illustrating the improved guide in its operative relation to the socket casing, and to the pull switch therein. Fig. 3 is an enlarged cross-sectional view on the line 3—3 of Fig. 1. Fig. 4 is a detail in perspective of the guide and the part of the shell to which it is detachably applied.

Like references designate corresponding parts in the several figures of the drawing.

The guide body may be of any suitable 55 form or configuration. However, it is pref-

erably of the usual horn or bell type, so that the same may be said to consist of a one-piece bell-member designated by the numeral 1, and having the outer flaring mouth and an inner reduced neck part. According to the present invention the inner reduced neck part of the guide body or bell-member 1 is rigidly united, in any suitable manner, to an attaching plate 2. This attaching plate may be of any suitable size or 60 shape, but is preferably of a general rectangular form to provide a supporting member or base that carries the guide body or bell-member and permits its ready attachment to and detachment from the socket casing.

To provide for the proper mounting of the guide attachment, it is preferable, in carrying out the present invention, to provide a slidable interlocking connection 65 between the attaching plate 2 and the shell 3 of the socket casing, said casing also including the usual cap 4 that is fitted to one end of the shell. This slidable interlocking engagement between the plate 2 and the shell-member 3 of the casing may be accomplished 70 in various ways, but a practical method is shown in the drawings and consists in constructing the plate 2 at opposite side edges with spaced flanges or equivalent elements 5 which form therebetween retaining grooves 75 which engage over or receive the opposite side edges of a resilient slot 6, formed in the shell 3, and opening through one edge thereof, said slot being disposed longitudinally 80 of the shell and corresponding to the usual key slot with which the casings of key sockets are ordinarily provided. It will 85 thus be seen that by slidably interlocking the plate 2 with the edges of the slot 6, the said plate may be moved to a covering position over the slot and held there by the attachment of the cap 4 upon the shell. In this position the guide body or bell-member 1 receives and guides therethrough the usual pull-chain 7 of the pull-switch S, carried by the switch body B located in the socket casing.

It will also be apparent that upon the removal of the socket cap, not only the switch is freely accessible and removable, but also the guide attachment may be 95 quickly and easily removed for reburnishing purposes, and also to facilitate the removal of the chain if necessary.

In the foregoing description, the principal 100 features of construction, namely, the bell

member 1, the attaching plate 2 and the holding elements 5 have been referred to in a general way, but from a manufacturing standpoint the several parts are preferably 5 constructed and arranged as shown in the accompanying drawings, in which the bell member 1 proper is shown as being nested within an outer sleeve 7, said sleeve and the bell member proper being formed with or 10 secured to flange elements at their inner ends, which elements are arranged in spaced relation to provide the spaced flanges 5 previously referred to. In this form of construction, the bell member 1 is preferably 15 provided at its outer edge, with an edge

flange 8 that is clenched over the outer end of the sleeve 7.

I claim:

A pull chain guide comprising an outer sleeve member, a bell-member proper nested within said sleeve member, said sleeve and bell-members being provided at their inner ends with flanges spaced apart to provide retaining means for the guide. 20

In testimony whereof I hereunto affix my 25 signature in the presence of two witnesses.

EDGAR H. FREEMAN.
